CIRCULAR RIB KNITTING MACHINE AND
METHOD OF OPERATING SAMERoscoe Hill, Hamilton, Ontario, Canada, assignor
to Scott & Williams, Incorporated, Laconia,
N. H., a corporation of Massachusetts

Application April 11, 1939, Serial No. 267,290

6 Claims. (Cl. 66—13)

This invention relates to circular rib knitting machines and methods of manipulating same, and more particularly to such machines when equipped in the dial with independent latch needles. These needles may be the compound needles such for example as disclosed in the Robert W. Scott Patent No. 1,641,101, dated August 30, 1927.

One object of my invention is to produce rib dial independent latch needle hosiery machines adapted to make ribbed instep hosiery. The invention is an improvement on the ribbed instep machine of the Robert W. Scott Patent No. 1,641,554, dated September 6, 1927. It will be shown embodied in the half hose machine of the Scott Patent No. 1,641,101.

It is desirable to knit seamless hosiery from top to toe in order to have a selvage edge or a turned welt at the top of the stocking, and in the case of ribbed hosiery it is especially desirable to knit from top to toe because the present day machines for knitting from toe to top have a greater number of wales in the ribbed fabric than in the plain fabric. This is not true of ribbed hosiery made on machines which knit from top to toe.

An object of my invention is to produce a machine whose manipulation of the needles during transfer in the making of ribbed instep hosiery is such that perfect goods can easily be produced. It is characteristic of my invention that the special manipulations necessary to prevent transfer on the instep dial needles when transferring loops from the heel dial needles to the cylinder needles, in no way affect the portions of the instep dial needles on which loops are being carried at that time. Thus the applicant manipulates the castoff or transfer element so that it does not take the stitch from the stitch-drawing element.

The invention will be shown and described in connection with the two-part or compound needle shown in the Scott Patent 1,641,101, above-mentioned.

In the drawings:

Fig. 1 is a schematic plan view of certain of the dial cams and needles of a machine of the well known Scott & Williams revolving needle cylinder type adapted to knit ribbed instep stockings from top to toe in accordance with my invention, the arrows showing the direction of movement of the dial needles;

Fig. 2 is a vertical view in enlarged section through one side of the dial, taken on the line 2—2 of Fig. 1, showing the hook of an instep dial

needle ready to give up its loop to the castoff, but the latter so advanced ahead of its normal time of movement that it cannot take the loop from the hook;

Fig. 3 is a view similar to Fig. 2, taken on the line 3—3 of Fig. 1, showing a later stage of the manipulation of an instep dial needle when transferring from the heel dial needles, the hook being shown retracted with the loop in it instead of in the notch adjacent to the point ^{n^o} 10 from the castoff as in normal transferring;

Fig. 4 is a view in side elevation of the dial and associated parts, showing the elements for controlling the special transfer cam for the instep castoffs; while

Fig. 5 is a plan view of the dial and control elements shown in Fig. 4.

In the ordinary revolving needle cylinder hosiery knitting machine the needle butts are shorter on the heel side of the cylinder than on the instep side for the purpose of facilitating the manufacture of heels and toes. This fact has been taken advantage of heretofore in obtaining transfer of loops from dial needles on the heel side without simultaneously transferring loops from dial needles on the instep side. This was done by allowing all the dial needles to pass through the transfer cams while varying the manipulation of the instep dial elements carrying loops sufficiently to make transfer of their loops ineffective. In transferring a loop from a two-part dial needle to a cylinder needle in a modern rib hosiery machine, it is customary for the hook portion of the needle to give up its loop to the castoff portion of the needle, and the castoff portion in turn presents the loop to the cylinder needle. This transfer from hook to castoff requires accurate timing of the movements of the two parts, and owing to the necessity that these same two parts at other times must perform ordinary knitting of rib stitches, the timing and positioning of the parts in this transfer operation must be accurate. The improvement thereon heretofore referred to consisted in withdrawing the hook of the dial needle from the position in which the castoff could take the loop prior to the time when the castoff would normally take the loop from the hook. Since the cam which brought the hook to this presentation position must be the same one which brings the heel dial needle hooks to presentation position to cause effective transfer of these loops, the amount of time available to retract the hook on the instep side before the castoffs are pushed out to take the loops away from the hook is quite

15

short. The difference in position between effective and ineffective transfer therefore is slight, speaking in terms of linear distance. Furthermore, the necessary moving of the loop down into the hook proper of the hook portion is retarded by the proximity of that loop to the preceding stitches which are still on the upper edge or shank of the hooks. If one stitch on the instep side should be caught by the castoff it would be broken, thereby spoiling the stocking. All these difficulties are avoided by my improved arrangement of the cams and manipulation of the dial needles.

In the embodiment shown in the drawings I have illustrated two-part needles comprising hook portions *a* and castoffs *b* operated independently of each other in a radial direction to cause knitting or transfer of rib stitches to the cylinder needles, as may be required. For this embodiment of my invention the hooks and castoffs are unchanged from that of the Scott Patent 1,641,101, but the cams in the dial for manipulating the hook and castoff are different and the manipulation of the two parts is also different. The manipulation of the cylinder needles is unchanged. It should be understood that any two-part needle may be used in the dial.

In the machine of the Scott Patent 1,641,101, to which patent reference is made for any parts not shown in the present drawings, there are twice as many cylinder needles *n* as there are dial needles. This is assuming that the rib fabric is to be "one and one" fabric. When changing from rib to plain fabric, every other cylinder needle receives a dial needle loop. These cylinder needles are the ones without jacks under them, as described in Scott 1,641,101. As seen in Fig. 2, each part of the two-part dial needle has its own operating butt, the butt for the castoff *b* being the radially outer of the two. The dial needles corresponding to the heel of the stocking have low butts, and the dial needles corresponding to the instep side have high butts. The high butts of the instep needle hooks are designated in the drawings by the reference character *n*¹⁰, and the high butts of the castoffs on the instep side are designated by the character *n*¹⁶. The cap *D'* of the dial *D* which is shown schematically in Fig. 1, is hollowed out to form a broad, concentric groove, as usual,—the operating butts of both castoffs and hooks lying in this broad groove and being operated by the edges thereof as well as by the cams lying between the two edges of the groove. The cams 10, 12, 13 and 14 are the usual ones for causing knitting, as shown and described in detail in the Scott Patent 1,641,101. It will not be necessary to refer further to these in this specification other than to say that the cams 12 and 13 are for pushing out the castoffs and hooks respectively, prior to receiving yarn for the new stitch. It might be noted that when the hook part of the dial needle has ridden up cam 13, the previous dial loop will have slipped up on the upper edge of the shank of the hook member until it is in position to be entered by the inner or rear point *n*¹⁷ of the castoff. The cam 14 is a fixed separator cam. The cam 10 is for operating on both the hooks and the castoffs after the new yarn has been taken, the point 11 operating on the castoffs.

Turning now to the cams involved in the transfer operation, we find that the machine contains the usual transfer cam 16 for pushing out the

hook *a* of the dial needle to effect transfer, and the transfer cam 17 for retracting the hook after the loop has been taken by the castoff *b*. These two cams are supported in a block and operated by a lever, in the same manner as shown in Fig. 5 of the Scott Patent 1,641,101. These two cams are manipulated as in that Scott patent, i. e., they are inserted half way at the beginning of the transfer operation so that they contact the high butt dial needles and when in the middle of the high butts they are inserted the rest of the way so that by the time the low butt dial needles reach them they can operate them.

The new transfer cams comprise two fixed or permanent cams 18, 19 and a movable cam 20. The fixed cam 18 merely holds the hooks *a* of the dial needles in their retracted position until it is time for the pushout cam 16 to operate on them, while the fixed cam 19 located at a point subsequent to the movable cam 20 assists that cam 20 in performing its operation. Its inner edge prevents the castoffs from being carried out prematurely by friction between them and the hook portions when the hook portions are protruded by cam 16. This special cam 20 is so located in a notch on the outer side of the fixed cam 18 that it serves to push outwardly—at a point in advance of the pushing out of the hooks by the cam 16—all the castoffs which have high operating butts *n*¹⁶. It delivers those high operating butts to the fixed cam 19 which, in the embodiment shown in the drawings, pushes the castoffs out a little further and then holds them in that outward position until the needles are opposite the outer edge of the regular transfer cam 17. The outer edge of cam 17 is so located as to maintain the castoffs in this outer position until they pass beyond the cam and engage the outer edge of the broad groove. This special cam 20 is movable vertically in a slot 629 through the dial cap *D'*, which cap and dial are supported on the dial spindle *d*. The cam is carried by a bracket 625 movable vertically on a stationary rod 630 above the dial cap *D'*, and there is a compression spring 627 on this rod 630 tending to keep the bracket and cam in raised position. The bracket and cam are lowered by a lever 626 overlying the cam and operated from cams on the main pattern drum 120 (see Patent 1,641,101). The extent to which this cam can be raised is adjustably fixed by a limit stop 628 carried on a post on the dial cap *D'*. The maximum degree of insertion of this cam brings it into contact with the high operating butts of the instep dial needles only—it cannot be inserted to a level where it will contact the low butts of the heel dial needles.

As can be seen in Figs. 2 and 3, the hook part *a* of the dial needle has an upper edge *n*⁷ and the hook *n*⁶ itself is bent backwardly so that the point thereof is slightly below the upper face or edge of the shank. The ledge on the lower edge of the castoff *b* contacts the upper edge *n*⁷ of the shank and the points *n*¹⁷ and *n*²⁰ of the castoff, which face rearwardly and forwardly respectively, just clear the top of the hook *n*⁶. There is an arcuate face *n*¹⁸ in back of the rear point *n*¹⁷ of the castoff, which may be termed the throat of the castoff, and the forward or outer point *n*²⁰ may be termed the transfer point. The stitches of the fabric being knit are shown at *F*, and the loop on the dial needle is indicated by *f*²¹, and the loop on the cylinder needle by *f*²⁰.

Assuming that the fabric is being knit from top

to toe and that a point just prior to the heel has been reached at which it is desired to cease the making of ribbed fabric on the heel side, but that it is desired to continue the knitting of ribbed fabric on the instep side, the method of manipulation in accordance with my invention will be as follows. The cams 16 and 17 are lowered by their controlling elements in response to a cam on the main pattern drum until those two cams 10 will operate on the high butt dial needles. This occurs while the low butt dial needles are passing under the cams. Simultaneously with the introduction of cams 16 and 17 the special cam 20 is lowered by its lever 626 until it also is in position 15 to operate on the high butts. It is noted that cam 16 operates on the high butt n^{10} of the hook part a of the instep needle, cam 20 operates on the high butt n^{16} of the castoff b of the instep dial needle, while cam 17 functions with regard 20 to both the hooks and castoffs of the instep dial needles. Cam 20 pushes the castoffs out while the hooks a are held in by the inner side of stationary cam 18. This brings the castoffs out to the position shown in Fig. 2, where the transfer 25 points n^{20} are radially outside the cylinder needles n . This is in advance of the time when the castoffs would normally be projected this far. Shortly thereafter the regular transfer cam 16 projects the hooks a at the regular time, and the 30 loop f^{21} rides up out of the hook n^a of the part a to the position shown in Fig. 2, where it is in the throat or arcuate portion n^{18} of the castoff and behind the transfer point n^{20} . This brings all 35 the parts to the position of Fig. 2, and it will be noted that the castoff cannot pick up the loop f^{21} . In this way effective transfer has been prevented without in any way disturbing the normal transfer operation of the parts of the machine on which the loops are located.

40 As rotation of the machine continues, the hooks a are drawn in by the inner side of cam 17, and the spring bands on the sinkers, aided by a spring-pressed cam, push the fabric so that the loops ride down into the hooks n^a . The inner 45 end of cam 17 does not extend as far inwardly as usual so that the point of the hook n^a of part a is not drawn far enough inwardly to cast off the loop in case of possible failure of the spring band or spring-pressed cam to push the loops down into the hooks n^a before the needles reach cams 50 12 and 13 where the needle parts start outwardly to receive new yarn. When the middle of the high butt or instep group of dial needles is under the cams 16, 17, these two cams are pushed in all 55 the way so that when the low butts reach them they will transfer their stitches to the cylinder needles in the usual way.

Cam 20 is removed when the low butt needles are being operated to transfer their stitches by 60 cams 16 and 17. Cams 16 and 17 are raised part way when the high butt instep needles are being operated during the following or a succeeding revolution to miss the low butt needles and are raised all the way when the low butt needles are 65 under them. At the same time that cam 20 is removed cams 10 and 12 are operating the high butt needles and are raised part way so that the low butt needles will not be advanced to knit after being transferred.

70 Cams 10 and 12 are removed during the heel and again inserted part way to operate the high butt needles to make ribbed fabric in the instep, during the foot, the sole being plain fabric, until the ring toe is reached. At this point cams 16 75 and 17 are inserted, i. e., lowered, until they are

in line with the high butts, at which time they transfer the high butt stitches to the cylinder needles.

It will be noted that in accordance with this invention I have given special manipulation to an 5 element which has no loop on it at the time of the manipulation, and that the special movement is merely to move the castoff radially outward to its outermost position at an abnormally early point so that the elements carrying the 10 loops can carry through their movement in the regular time and still have the transfer ineffective as far as concerns the high butt needles. It should also be noted that having made this abnormally early movement to carry the part 15 that was to receive the loop beyond the crucial transfer point from hook to castoff, any slight variation in the movements of the parts is harmless.

What I claim is:

1. In a circular hosiery rib knitting machine, independent cylinder and dial needles and means to transfer loops from dial to cylinder needles, each dial needle comprising a plurality of portions movable relatively to each other, the loop 25 being on one of the portions of the dial needle at the beginning of the transfer operation, in combination with means adapted to vary the time of movement of portions which are free of loops of one or more of the dial needles to prevent presentation of the loops of such dial needles to the cylinder needles.

2. In a circular hosiery knitting machine, independent cylinder and dial needles and means to transfer loops from dial to cylinder, each dial 35 needle having two parts, the loop being transferred from one portion to the other by relative movement therebetween and thence to the cylinder needle, in combination with means advancing the time of loop taking from one dial needle 40 element to the other so as to make transfer impossible.

3. In a circular rib knitting machine, independent cylinder and dial needles, cam means to cause transfer of loops from dial to cylinder 45 needle, each dial needle having two parts and the cam means causing transfer from one part to the other by relative movement between the two parts and thence to the cylinder needle, in combination with auxiliary cam means adapted 50 to prevent transfer of the loop from one part of the dial needle to the other by giving it the loop-taking movement abnormally early.

4. In a method of operating a circular rib knitting machine having two-part dial needles, the 55 method of causing transfer of dial stitches to cylinder needles on some of the needles only which comprises passing all the dial needles through transfer operations while varying the movement of the non-loop carrying parts of certain of the dial needles sufficiently to prevent effective transfer on those needles.

5. In a method of operating a circular rib knitting machine having two-part dial needles, with castoff and stitch-drawing elements, the 65 method of causing transfer of dial stitches to cylinder needles on some of the needles only which comprises passing all the dial needles through transfer operations while causing the castoff elements of certain of the dial needles to miss their transfer by making their transfer movement abnormally early.

6. In a circular rib knitting machine, a cylinder and a dial, independent latch needles in said cylinder and dial needles in said dial, each 75

comprising a hook and a castoff movable relatively to each other, cam means adapted to cause said castoffs to present their loops to the cylinder needles for transfer, in combination with operating butts of two heights on said castoffs and a special cam movable into operative relation with

the high butt castoffs only adapted to cause projection of each high butt castoff abnormally early beyond the position for taking the loop from the hook whereby the castoffs are prevented from taking their loops from the hooks.

ROSCOE HILL.
